INVENTOR

BY Victor J. Evans

ATTORNEY

UNITED STATES PATENT OFFICE

EDWARD R. UCHIYAMA, OF SACRAMENTO, CALIFORNIA

GAME APPARATUS

Application filed May 15, 1929. Serial No. 363,345.

This invention relates to improvements in game apparatus.

An object of the invention comprehends the provision of game boards.

5 Another object of the invention contemplates the arrangement of the game boards in sections whereby the latter may alternately provide standards for the companion sectional game board.

10 Another object of the invention embodies brace members for the board sections.

A further object of the invention consists of a locking mechanism for the board sections when set up for active use.

15 With the above and other objects in view, the invention further consists of the following novel features and details of construction, to be hereinafter more fully described, illustrated in the accompanying drawing and 20 pointed out in the appended claims.

In the drawing:—

Figure 1 is a perspective view of the invention set up for use.

Figure 2 is a top plan view of the invention 25 with the supporting structure as shown in Figure 1 folded to provide a game board.

Figure 3 is a detail sectional view taken through the frame and hinge mountings for the game board sections thereon.

30 Figures 4 and 5 are elevations of different forms of game pieces.

Referring to the drawing in detail where- 35 in like characters of reference denote corre- sponding parts, the reference character 10 indicates a frame of rectangular shape. The companion sections 11 and 12 of a game board A and the sections 13 and 14 of a game board B are provided with peripheral flange 40 portions 15 to be extended over the outer side of the frame 10 when folded thereon in the manner suggested in Figures 1 and 3 of the drawing.

Hinges 16, having plates 17, 18 and 19 re- 45 spectively, are connected with the outer sides of the flange portions 15 of the sections B and A and the frame 10 respectively as evidenced from the illustration of my invention in Figure 3 of the drawing. These mountings will permit of alternate extending of the sections 50 of the game boards in parallelism to pro-

vide standards for the game boards in use, as shown in Figure 1 of the drawing.

Disk members 20, pivotally mounted upon pins 21 carried upon the outer sides of the frame 10 adjacent the meeting ends of the 55 sections for the game boards, are provided with a multiplicity of slotted portions 22 radially and concentrically disposed from the peripheries thereof to accommodate studs 23 carried upon the outer sides and adjacent the 60 meeting ends of said game board sections. All of the studs may be inserted within the slots or cut-out portions 22 at the same time and partial rotation of said disks will simultaneously lock all of the studs whereby 65 one locking device will serve four game board sections.

Brace members 24, carried by and swing- 70 ably mounted upon the inner side of the frame 10, are adapted for detachable locking con- nection at their opposite ends with the inner sides of the depending flange portions upon the game board sections when employed as legs or supports. The braces 24 occupy the 75 Figure 3 position when the game board sec- tions are folded upon the frame and locked together. Obviously the compartment as defined between the closed sections of the game boards may be effectively employed for carrying and containing game pieces of any 80 nature desired.

The game pieces illustrated in Figures 4 and 5 of the drawing, and as indicated generally and identified by the numerals 25 and 26 respectively, are large and small and ar- 85 ranged in groups having legends or other characteristics to identify each group belong- ing to individual players in order that the game pieces will not be mixed up while in use and no controversies may arise as be- 90 tween players concerning the property right of the game pieces. The different faces of the game board sections 11, 12, 13 and 14 of the game boards A and B respectively may 95 be arranged in squares of different colors and bearing different numbers or other characteristics or may be striped or otherwise pro- vided with coloring lines which must be cov- ered by the game pieces or approach within 100

given distances thereto before credit may be allowed for the individual shots.

Obviously the game boards and game pieces therefor may be faced with different characteristics and legends in order that any number and type of game may be played.

When pitching the game pieces upon the game board sections, the legends are first discounted in the following manner.

- 10 Circle wins from square.
- Square wins from triangle.
- Triangle wins from circle.
- 15 The color surfaces of the section 14 are then considered and the colorings as between 15 contesting game pieces are calculated in the following manner.
- Red wins from white.
- White wins from blue.
- Blue wins from red.
- 20 Contestants in the game could hold the game pieces backs up while playing and are only turned face up until the game is finished and the score calculated.

The invention is susceptible of various 25 changes in its form, proportions and minor details of construction and the right is herein reserved to make such changes as properly fall within the scope of the appended claims.

30 Having thus described the invention, what is claimed is:—

1. A game apparatus comprising a frame, game boards of sectional formation hingedly mounted upon opposite sides of said frame, 35 each game board comprising two sections hinged to opposite edges of one side of said frame and having flange portions carried upon their outer sides to overlie the adjacent portions of said frame, the sections of either 40 game board being movable on their hinges to a position at right angles to the frame to serve as legs for the frame and the other game board, and brace members carried by said frame and adapted for attachment to 45 the leg forming sections.
2. A game apparatus comprising a frame, game boards of sectional formation hingedly mounted upon opposite sides of said frame, each game board comprising two sections 50 hinged to opposite edges of one side of said frame and having flange portions carried upon their outer sides to overlie the adjacent portions of said frame, the sections of either game board being movable on their hinges to 55 a position at right angles to the frame to serve as legs for the frame and the other game board, brace members carried by said frame and adapted for attachment to the leg forming sections, and locking members carried by the frame common to all of the game board sections.

In testimony whereof I affix my signature.
EDWARD R. UCHIYAMA.
